HENRY CAVE, OF HARTFORD, AND WALTER H. RUDOLPH, OF WEST HARTFORD, CONNECTICUT, ASSIGNORS TO THE FULLER BRUSH COMPANY, OF HARTFORD, CONNECTICUT, A CORPORATION OF CONNECTICUT

PROCESS FOR MAKING CLEANING IMPLEMENTS

Application filed January 30, 1925. Serial No. 5,766.

This invention relates to a process for the production of floor mops, brushes and similar cleaning implements, and an object of the invention, among others, is the making of devices of this character in a particularly rapid, efficient and economical manner.

One form of mechanism contemplating the process herein set forth and in the use of which the objects herein set out, as well as others, may be attained, is illustrated in the accompanying drawings, in which—

Figure 1 is a view in section through the forming devices of a machine constructed to carry out this improved process, and illustrating an initial step in the process.

Figure 2 is a view similar to Figure 1, but illustrating an advanced step in the process.

Figure 3 is an end view of a portion of the forming device and a sectional view of other parts thereof looking from a point located at right angles to the point of view of Figure 1.

Figure 4 is a view similar to Figure 3, but illustrating a step further advanced in the process.

Figure 5 is a similar view illustrating another further advanced step in the process.

Figure 6 is a view in section through the parts shown in Figure 5, and illustrating the same step in the process as that shown in Figure 5.

Figure 7 is a side view of a portion of the cleaning implement resulting from the practice of this improved process.

Figure 8 is an end view of the same.

The process forming the subject matter of this application contemplates the production of a cleaning implement, such as a floor mop, brush or similar article, having a base within which the cleaning material, as cotton threads, bristles, hair or other fibers are secured by extending such fibers around a core of metal or other suitable material that is encased within and secured to the base, the free ends of the cleaning material projecting from such base, the process contemplating the bending of the material forming the base into a trough shaped structure and then pressing the cleaning material intermediate the ends thereof into such trough-shaped

structure, the core being placed upon such material and the side parts of the casing comprising the base being then pressed together to securely fasten the core and cleaning material in place.

In the drawings forming a part of this application there is shown one form of mechanism comprising dies and other members for performing the operations above set out, in such drawings the numeral 8 indicating a die holder for a die 9 that is secured to the holder in any suitable manner and has a groove 10 to receive a blank 11 of sheet metal or other suitable material that is placed upon a stationary punch 12 with the edges of the blank resting upon spring supports 13—14 seated in a base block 15 that may be supported in any suitable manner. The die holder 8 may be pressed downwardly in any suitable manner, the structure herein shown contemplating a head 16 (see Figure 5) that has a reciprocating movement and makes contact with the holder to force it to the position shown in Figure 2 thereby bending the blank into trough shape.

This trough shaped blank is then located between main closing dies 17 pivotally supported on a die block 18, which block may also be attached to the head 16. A base block 19 is located underneath the dies 17 and has guides 20 for a plunger 21 having reciprocating movement therebetween, said guides also having actuating projections 22 for the dies 17. End closing dies 23 are pivotally supported at opposite ends of the dies 17, it being understood that the die 9, punch 12, closing dies 17 and plunger 21 are of a length substantially that of the width of the cleaning material 24 that is to be secured within the base 25 of the cleaning implement. The plunger 21 may be reciprocated in any suitable manner, as by means of an arm 26 connected with the lower end of the plunger and operated as by means of a rock shaft 27. A core 28 of wire or other suitable material, in the final operation is located in the loop formed by the cleaning material and inclosed within the base 25, in the mechanism herein shown for effecting this purpose, this core being placed upon the plunger 21 by which the

core is forced against the material 24 together with which it is pushed into the trough shaped blank 11. This core is preferably a little shorter than said blank, but of 5 a length greater than the width of the material 24, the ends of the core terminating just within the tubular ends of the blank when finally bent.

When the process is carried out by the 10 mechanism herein illustrated and described, the blank 11 is first placed upon the punch 12 and spring supports 13-14, and the die holder 8 being forced downwardly the blank 11 is formed to trough shape, as shown in Figure 15 2. This trough shaped blank is then placed between the closing dies 17, and as shown in Figure 3, the ends of the blank being located between the end closing dies 23 that are located at each end of the dies 17, the cleaning 20 material 24 is extended across the guides 20 and the wire comprising the core 28 is placed upon the plunger 21. The die block 18 being now forced downwardly as by the operation of the head 16, the end closing dies 23 25 push a portion of the material 24 into contact with the central portions of the guides 20, further downward movement of this structure causing the inclosing dies to assume the position shown in Figure 4 and with the rest 30 of the material 24 pressed against the guides 20. The arm 26 is operated to move the plunger 21 with the core 28 and the central portion of the material 24 thereon into the space within the blank 11 and between the ends of 35 the dies 23 prior to the time that said dies press said material into contact with the guides 20, this operation taking place preferably at about the time the plunger begins its downward movement. This pressure of 40 the guides 20 against the material in the operation of closing the dies 23 not only holds the material by reason of an inherent stiffness therein, against the bottom of the groove in the blank, but said pressure crowds the material 45 and maintains the fold thereof tightly in contact with the bottom of said groove. Further downward movement of the parts moves both the end closing dies and the main closing dies 17 into the position shown in 50 Figures 5 and 6 thereby forming the base 25 into the shape shown in Figure 7 with the portion of said base intermediate its ends having a slot through which the material 24 extends and the edges of the ends 29 being 55 forced together and closely against the core 28, as shown in Figure 8.

In accordance with the provisions of the 60 patent statutes we have described the principles of operation of our invention, together with the process which we now consider to represent the best embodiment thereof; but we desire to have it understood that the process described and device shown are only illustrative and that the invention may be carried 65 out by other means as fall within the scope

of the appended claims and applied to uses other than those above set out.

We claim—

1. The process for forming a cleaning structure that consists in bending a blank to comprise a base into trough shaped form, placing the folded portion of a mass of cleaning material with a core within said fold in the trough of said base, with an end of the core projecting beyond the end of said mass, and then closing the edges of said base intermediate its ends against said material and closing the edges of the base at the ends of said mass substantially into contact along the projecting end of said core. 70

2. The process for forming a cleaning structure that consists in bending a blank to comprise a base into trough shaped form, placing the folded portion of a mass of cleaning material in said base, placing a core with- 75 in the fold of said material with an end of the core projecting beyond the end of said mass, and then simultaneously closing the edges of said base intermediate its ends into contact with the material and the edges of the 80 base at the ends closer together along the projecting ends of said core. 85
